AUGUST PHILIP SEISS, OF OMAHA, NEBRASKA, AND GEORGE WILLIAM ROHRIG, OF COUNCIL BLUFFS, IOWA.

COMBINED SPARK-PLUG, PRIMER, AND INDICATOR.

1,108,009.

Specification of Letters Patent. Patented Aug. 18, 1914.

Application filed March 25, 1913. Serial No. 756,649.

To all whom it may concern:

Be it known that we, AUGUST P. SEISS, a citizen of the United States, and a resident of Omaha, in the county of Douglas and State of Nebraska, and GEORGE W. ROHRIG, a citizen of the United States, and resident of Council Bluffs, in the county of Pottawattamie and State of Iowa, have invented a new and Improved Combined Spark-Plug, Primer, and Indicator, of which the following is a full, clear, and exact description.

Our invention relates to spark plugs for internal combustion engines, and it is a design of the invention to provide a spark plug and appurtenances which, in addition to the usual functions of the plug in producing the ignition spark, will serve as a primer and also serve to indicate whether a particular cylinder is doing its work, or doing it properly.

It is also a design of our invention to provide a device of the indicated character, efficient in operation, and characterized by simplicity of adjustment and control.

The distinguishing features of the invention, and the important structural elements characterizing the preferred embodiment which is illustrated as an example, will be more particularly explained in the specific description hereinafter to be given.

Reference is to be had to the accompanying drawings forming a part of this specification, in which similar characters of reference indicate corresponding parts in all the views.

Figure 1 is a vertical section of a combination spark plug, primer and indicator embodying our invention, and showing the same applied; Fig. 2 is a fragmentary vertical section showing an adjustment of the valve means whereby the device can be employed as an indicator to test whether the cylinder is working properly; Fig. 3 is a similar view showing the adjustment for the device to constitute a primer; and Fig. 4 is a plan view of the parts shown in Figs. 2 and 3.

In constructing our device in accordance with the illustrated example, the body 10 of the plug is made of a form to be received in the cylinder A, and provided with a core 11, insulated from the body 10 by the sleeve 12, the said body and core being provided at the inner end with terminals 13, 13^a. The

insulating sleeve 12 may be held to the body 10 in any suitable manner, as by a bonnet 14 which clamps the lateral flange 12^a of the sleeve against the upper end of the body, there being desirably a packing 15 between the bonnet and shoulder. Near the lower end of the core 11 a lateral shoulder 16 is formed to receive a suitable packing 17. The upper end of the core is threaded, as at 11^a, and receives outside of the sleeve 12, a nut 18, the tightening of which draws the inner shouldered end of the core against the packing 17 which is seated on a shoulder 12^a formed on the interior of the sleeve 12. A clamp nut 19 is received on the threaded end 11^a of the core, above the nut 18, and serves in practice, the double purpose of a lock nut and as a means to clamp a conductor wire (not shown) between the nuts. The core 11 is made tubular, being provided with a through axial bore 20, and mounted on said core is a valve casing 21 which has an axial through-bore 22 in line with the bore 20 of the core 11, and forms a continuation thereof.

The upper end of the valve casing is in the form of a primer cup 23, the bottom of which communicates with the bore 22 of the valve casing. Fitted in the valve casing 21 is a valve 24, illustrated as a cock having a transverse passage 25, which, by the turning of the valve, may be brought into register with the bore 22 of the valve casing, or disposed transversely thereon to close said bore and thus close the tubular core of the spark plug, as hereinafter further described. The passage 25 in the valve 24 is contracted at its inner end to provide a valve seat 26 on which an auxiliary valve 27 is adapted to seat, said auxiliary valve being capable of play in the passage 25 toward and from the seat 26.

In connection with the valve 24 and its passage 25, by-passes are produced for the purpose of permitting a priming charge to pass from the cup 23 to the tubular spark plug, and for providing in another adjustment of the valve 24, for observing the workings of the cylinder, by permitting a portion of the products of combustion of an exploded charge to pass around the auxiliary valve and through the main valve outwardly through the primer cup to indicate whether the cylinder is working or working properly. Thus a by-pass 28 in

the valve 24 parallels the passage 25 and communicates with the latter, being in the nature of a lateral enlargement of said passage 25, at one side thereof. Similarly a 5 by-pass 29 is formed in connection with the bore 22 of the valve casing, adjacent to the bottom of the priming cup 23, so that when the valve 24 is turned to the position shown in Fig. 2, the auxiliary ball valve 27 is free 10 to rise in response to an explosion in the cylinder, so that a portion of the products of combustion will pass around the valve through the by-passes 28, 29, and out through the priming cup, to indicate 15 whether the particular cylinder to which the plug is affixed is properly performing its functions. A third by-pass passage 30 is formed in the bore 22 of the valve casing below the valve 24, and when the valve 24 is 20 turned to the position shown in Fig. 3, the by-passes 28, 30, will be in register with each other, and there will be a clear passage from the priming cup through the main valve passage 25, and the by-passes 28, 30, to 25 the spark plug, for the delivery of a priming charge around the auxiliary valve 27.

The valve 24 has a lever handle 31 for turning the valve, and in practice, said handle will bear on one side the word Indicator, 30 and on the opposite side the word Primer, as indicated in Fig. 4, and when said handle is turned to the vertical position the spark plug will be closed and free to perform its usual functions in the ordinary manner. If 35 the handle be turned upwardly in one direction, say to the left, as in Figs. 2 and 4, the valve means 24, 26, will be so disposed as to allow the device to function as an indicator; while if the handle 31 be turned 40 to the right, as in the dotted lines position in Fig. 4, and as shown in Fig. 3, the device may function as a primer. The valve 24 has any approved means for holding it tightly in place, being provided, for instance, with a stem 32 at the end opposite the handle 31, which stem receives washers 33, 34, between which is a helical spring 35, a cotter pin 36 being employed to retain the washers and spring in place.

50 Having thus described our invention, we claim as new, and desire to secure by Letters Patent:

1. A spark plug having an axial through-bore, a priming cup communicating with 55 said bore, a valve mounted to turn on an axis transecting the bore and formed with a transverse passage that is adapted to be brought into or out of register with the said bore and with the priming cup, and an outwardly-opening auxiliary valve commanding the passage in the main valve, the main valve being movable, to a closed position, to 60 an open position with the auxiliary valve on its seat, or to a position with the auxiliary valve below its inverted seat

to permit the auxiliary valve to rise toward its seat under the influence of fluid pressure in the spark plug, a by-pass to permit products of combustion charge through the main valve and past the seated auxiliary valve in the third mentioned position of the main valve. 70

2. A spark plug having a bore, a priming cup in communication with said bore, a main valve having a passage and adapted 75 to be turned to establish or cut off communication between the spark plug and priming cup, and an auxiliary valve in the passage of the main valve, there being a by-pass which, when the main valve is turned in 80 one position, will pass fluid around the auxiliary valve from the priming cup to the spark plug.

3. A spark plug having a bore, a main valve having a passage and adapted to be 85 turned to close or to open the said bore, and an auxiliary valve movable with the main valve and commanding the passage therethrough and responsive to fluid pressure in the spark plug, there being a by-pass, and 90 the auxiliary valve being movable, in one position of the main valve, to permit outflow by way of the by-pass.

4. A spark plug having a bore, a main valve having a passage adapted to be turned 95 to close or open the said bore, and an auxiliary valve movable with the main valve and commanding the passage thereof, and responsive to fluid pressure in the spark plug, there being a by-pass, and the auxiliary valve being movable, in one position 100 of the main valve, to permit inflow by way of the by-pass.

5. A spark plug, having a bore, a priming cup, and a valve means movable in one direction by gravity for cutting off communication from the priming cup to the spark plug, but movable in the opposite direction, in response to fluid pressure in the spark plug, to permit escape of products from the 110 spark plug through the priming cup. 105

6. A spark plug having a bore, a priming cup on the spark plug communicating with said bore, a main valve adapted to be turned to bring its passage into or out of register 115 with the said bore and cup, an auxiliary valve disposed in the passage of the main valve, there being a by-pass, and the auxiliary valve, in one position of the main valve being free to respond to fluid pressure 120 in the spark plug, and being movable, in response to such fluid pressure, to permit outflow, by way of the by-pass, from the spark plug to the priming cup.

7. A spark plug having a bore, a priming cup on the spark plug communicating with said bore, a main valve adapted to be turned to bring its passage into or out of register 125 with the said bore and cup, and an auxiliary valve disposed in the passage of the main 130

valve, there being a by-pass, and the auxiliary valve, in one position of the main valve being free to respond to fluid pressure in the spark plug to permit inflow by way of the by-pass from the priming cup to the spark plug.

8. A spark plug having a through-bore, a valve casing on said bore, a priming cup on said valve casing, there being a through-passage in the valve casing establishing communication between the bore of the spark plug and the priming cup, a main valve in the form of a cock mounted in the valve casing and formed with a passage adapted to be brought into or out of register with the passage of the valve casing, and an auxiliary valve in the passage of the main valve, there being a by-pass in the main valve communicating with the main passage, and 20 by-pass passages in the valve casing above and below the main valve and communicat-

ing with the through-passage of the valve casing.

9. A spark plug having sparking elements and a passage, a cock having a passage and turnable to bring its passage into or out of register with the passage of the spark plug, and an auxiliary valve in the cock and commanding the passage of the cock in one direction, there being oppositely disposed seats for the auxiliary valve on which said auxiliary valve rests according to the position of the turnable cock.

In testimony whereof we have signed our names to this specification in the presence of 35 two subscribing witnesses.

AUGUST PHILIP SEISS.
GEORGE WILLIAM ROHRIG.
